ROTARY IRONER

George W. Wardwell, Jr., Nichols, Conn., assignor
to General Electric Company, a corporation of
New York

Application April 3, 1937, Serial No. 134,850

10 Claims. (Cl. 38—59)

The present invention relates to ironers of the type in which ironing is effected by cooperating ironing members, one of which is a roll.

The object of my invention is to provide an improved construction and arrangement in ironers of this type, and for a consideration of what I believe to be novel and my invention, attention is directed to the accompanying description and the claims appended thereto.

In the accompanying drawings, Fig. 1 is a perspective view of an ironer embodying my invention; Fig. 2 is a sectional end elevation of the ironer housing showing the driving mechanism for the ironer; Fig. 3 is a sectional view taken on line 3—3 of Fig. 2; Fig. 4 is a sectional view taken on line 4—4 of Fig. 2; Fig. 5 is a sectional view showing the construction for controlling the rotation of the roll; Fig. 6 is a fragmentary front elevation of the ironer, broken away to show the construction of and the arrangement for driving the roll, the construction of and the arrangement for supporting the shoe, and the mechanism for rotating the roll and for moving the shoe toward and away from the roll; Fig. 7 is a sectional view taken on line 7—7 of Fig. 6; Fig. 8 is a sectional view taken on line 8—8 of Fig. 6; and Fig. 9 is a perspective view of the control lever and the linkage connected thereto controlling the operation of the ironer.

Referring to the drawings, the ironer comprises a frame or a housing 1 containing the driving mechanism for the ironer and provided with means for supporting a roll 2 and a shoe 3. The housing is provided with a flange 4 which rests on and is suitably secured to the top 5 of a suitable table.

As shown in Figures 6 and 7 the shoe comprises an arcuate metal plate 6 which is heated by suitable electric heating elements (not shown). On the upper surface of the plate 6 are secured a pair of studs 7 which extend through spacing sleeves 8 and a plate 9 resting on the ends of the sleeves. The studs 7 are spaced on each side of the center of the shoe and are arranged on a center line extending lengthwise of the shoe. A cover 10 covering the rear face of the plate 6 is clamped between the plate 9 and nuts 11 threaded on the studs. On the outside of the cover is a U-shaped bracket 12 which is fastened to the plate 9 by screws 13. The bracket 12 has a square seat 14 in which fits the squared end 15 of a circular rod or arm 16. The arm 16 extends from the housing 1 along the roll. Ears 17, struck out from each side of the bracket 12, confine the squared end 15 within the seat 14 and serve to

transmit pressure from the arm to the shoe when the shoe is pressed against the roll. When the shoe is pressed against the roll the shoe pivots about the points of contact between the ears 17 and the arm 16 to equalize the pressure between the roll and the shoe. Between one of the nuts 11 and the cover 10 is clamped a leaf spring 18 having fixed thereto a pin 19 which fits in a depression 20 in the squared end 15. The spring 18 yieldingly holds the squared end 15 of the arm 16 against the top surface of the seat 14. The spring 18 is relatively weak compared to the force exerted on the shoe when the shoe is pressed against the roll and it accordingly permits tilting of the shoe so that the pressure between the roll and the shoe is equalized throughout the surface of the shoe. The pin 19 prevents endwise movement of the shoe with respect to the arm 16. By depressing the end 21 of the spring the pin 19 may be moved clear of the depression 20 in which case the shoe may be slipped off the end of the arm 16.

The arm 16 extends through an opening 22 in the side wall of the housing 1 and the inner end is connected to a projection 23. Pivoted in the side wall of the housing is a lever 24 having a cam surface 25 which engages the upper side of the arm 16 and serves as a pivot for the arm. It is obvious that movement of the projection 23 in a vertical direction as viewed in Fig. 6 will cause the arm to pivot about the surface 25 and thereby cause the shoe to be moved toward and away from the roll. The arm is preferably made sufficiently resilient to decrease the variation in pressure between the roll and the shoe due to variations in the thickness of the pad and the material being moved. By pivoting the lever 24 in a clockwise direction as viewed in Figure 6, the surface 25 is moved clear of the arm 16 and the surface 26 is presented to the arm. Since the surface 26 is further removed from the arm 16 than the surface 25, the arm can now be moved away from the roll independently of the position of the projection 23. This provides an emergency release by means of which the shoe may be moved away from the roll. It also provides an arrangement which permits the movement of the shoe a relatively great distance from the roll so that the surface of the shoe will be more completely exposed. This makes the cleaning and waxing of the shoe more convenient.

The roll comprises a cylindrical metal shell 27 having a suitable padding 28 held on its outer surface by a pad cover 29. Within each end of the shell are disks 30 and 31 respectively pro-

vided with flanges 32 and 33 which are secured to the inner surface of the shell 21. In the flanges 32 and 33 are grooves 34 receiving snap rings 35 which secure the pad cover to the roll. At the center of each of the disks 30 and 31 are respectively secured cup-shaped members 36 and 36a carrying sleeve bearing 37 and 37a which rotatably support the roll on sleeves 38 and 38a. The sleeves 38 and 38a fit over and have their inner surfaces spaced from a tube 39 which is fixed in a boss 40 in the ironer housing. The sleeves 38 and 38a are prevented from turning on the tube 39 by means of pins 41 which extend through the tube. One end of the pins 41 rest in sockets 42 on the inner surface of the sleeves 38 and 38a and the other ends of the pin extend through holes 43 in the sleeves. Each of the sleeves is normally biased upward against the lower edge of the tube 39 by means of a coil spring 44 which surrounds the pin 41 and is arranged between a cup 45 fixed in the tube and a cup 46 on a sleeve 47 slidably carried in the tube. The upper end of the tube 47 bears against the inner surface of the sleeves and transmits the force of the coil spring 44 to the sleeves thereby moving the sleeves upward until they strike the lower surface of the tube 39. Under this condition an internal gear 48 which is fixed to the flange 33 is out of engagement with a pinion 49 formed on a shaft 50 which is journaled in a sleeve bearing 51 in the side wall of the ironer housing. The springs 44 are quite weak, since their only function is to lift the roll assembly to the position shown in Figs. 6 and 8. The shaft 50 is continuously rotated by means of a worm gear 52 which is pinned to the right end thereof.

When the shoe is pressed against the roll the pressure exerted by the shoe overcomes the force exerted by the relatively light coil springs 44 and moves the roll downward from the position shown in Figs. 6 and 8 to a position in which the gear 48 meshes with the pinion 49, thereby completing the driving connection to the roll and causing rotation of the roll. The movement of the roll can be described as transverse with respect to the axis of the roll and the roll support. The gears 48 and 49, therefore, function as a clutch which is operated by the pressure between the shoe and the roll to complete a driving connection to the roll. One advantage of this construction is that the gears 48 and 49 engage when the pressure between the roll is sufficient to overcome the relatively weak coil springs 44. The roll therefore starts turning before full ironing pressure is developed between the roll and the shoe. This decreases the starting load.

As the roll is moved to the position in which the gear 48 engages the pinion 49 there is some tendency for the teeth to jam. This tendency is increased by the fact that the gear 48 is an internal gear with its teeth extending radially inward and the pinion 49 is an external gear with its teeth extending radially outward. It is, therefore, possible for a pair of teeth on the pinion 49 to straddle a pair of teeth on the gear 48 in which case further approach of the gears would result in serious jamming. This tendency to jamming of the gear teeth is prevented by the arrangement for supporting the roll and the shoe.

When the shoe is away from the roll, the roll is held in a position in which the internal gear 48 is spaced from the pinion 49 by coil springs 44. These springs are relatively weak inasmuch as they need only be strong enough to lift the

weight of the roll assembly. This means that when the shoe engages the roll and moves it toward the tubular support 39, the pressure between the roll and the shoe at the start of this movement will be relatively light compared to the full ironing pressure. If there is any interference between the gear teeth which would prevent the teeth of the internal gear from going smoothly into mesh with the teeth of the pinion there will not be any very large forces built up between the gear teeth. Assuming that the roll and the internal gear 48 are moving toward the pinion 49 and that the ends of the teeth of the internal gear strike on the ends of the teeth of the pinion, the flexibility of the roll mounting combined with the tiltable mounting of the shoe allows the right end of the roll to pause sufficiently for the pinion to rotate and find its way into proper mesh with the internal gear. While the internal gear is pausing in its movement toward the pinion, the clearance between the ring 38 and the tube 39 allows the left end of the roll to move downward without building up any appreciable pressure between the teeth of the internal gear and the teeth of the pinion. This construction, therefore, obtains sufficient pause in the movement of the internal gear toward the pinion to prevent jamming of the gear teeth. From one aspect, the tiltable mounting of the roll can be regarded as a yielding mounting of the gear 48 which permits the gear to yield to prevent jamming of the gear teeth. The shoe does not prevent tilting of the roll since it is supported so that it can have a corresponding tilting movement.

Endwise movement of the roll on the tube 39 is prevented by a thrust washer 53 bearing against the end of the boss 40 and a thrust washer 54 which is held on the tube 39 by a pin 55. The thrust washers 53 and 54 bear against the ends of the cup-shaped members 36 and 36a.

When the ironer is used for ironing flat work it is desirable that the roll rotate continuously while the shoe is pressed against the roll. The rotation of the roll then feeds the material being ironed under the shoe. Under some circumstances, it is desirable that the roll remain stationary when the shoe is pressed against the roll. The rotation of the roll is prevented by a slide 56 which is slidable in a groove 57 in the boss 40. One end of the slide extends within the ironer housing and is provided with a slot 58 through which extends a crank 59 on a shaft 60 journaled in a boss 61 (Fig. 5) in the top wall 55 of the ironer housing. The shaft 60 projects outside the ironer housing and has pinned thereto a handle 62 by means of which the shaft may be rotated. The handle is yieldingly held in the position to which it is moved by means of a spring pressed ball detent 63 which cooperates with recesses in the surface 64 of the boss 61. The handle is held against the surface 64 by means of a compression spring 65 arranged between a washer 66 secured to the shaft 60 and the inner end of the boss 61. Rotation of the shaft 60 in a counterclockwise direction, as viewed in Fig. 6, causes the slide 56 to be moved to the left thereby moving a flange 67 on the left end of the slide between the tube 39 and the sleeve 38a. While in this position the flange 67 prevents movement of the sleeve 38a toward the tube 39 and thereby keeps the gear 48 out of mesh with the pinion 49 when the shoe is pressed against the roll. The roll will therefore remain stationary when the shoe is pressed against the roll.

The flange 87 cannot be moved to the position between the tube 39 and the sleeve 38a when the shoe is pressed against the roll. The flange 87 is moved from the position between the tube 39 and the sleeve 42 by movement of the shaft 50 in a clockwise direction, as viewed in Fig. 6. This movement of the shaft causes the slide 58 to be moved to the right. The movement of the slide in this direction is limited by engagement of the flange 87 with the end of the boss 48.

The ironer housing 1 has a vertical hollow portion 68 which serves as the frame or outer casing for the electric motor used to drive the ironing machine. The stationary member 69 of the electric motor is pressed into the hollow portion 68 and the rotary member 70 of the electric motor is carried on a shaft 71, the upper end of which is journaled in a bearing 72 carried in a web 73 and the lower end of which is journaled in a bearing 74 in a bearing housing 75 threaded into the lower end of the hollow portion 68. The bearing housing 75 carries a thrust ball 76 which supports the shaft. The web 73 which is integral with the housing forms a closure for the upper end of the electric motor. The motor shaft 71 projects above the bearing 72 and on its projecting end is cut a worm 77 which meshes with the worm wheel 52. As described above the worm wheel 52 is pinned to the shaft 50 and the shaft is accordingly continuously rotated by means of the worm 77 and the worm wheel 52. The right end of the shaft 50 is rotatably supported in boss 78 on a plate 79 secured to the end of the ironer housing. Movement of the shaft 50 to the left, as viewed in Fig. 6, is prevented by a washer 80 which engages the left wall of the ironer housing. The washer 80 is held on a shaft by means of a snap ring 81.

Rotatably carried on the boss 78 is a cam 82 which is provided with diametrically opposite radial slots in which are slidably carried clutch keys 83 (Fig. 3). The keys are urged outward by means of springs 84 and the outward movement is limited by flanges 85 on a plate 86 fixed to the cam 82. When the keys are in the inner position shown in Fig. 3, there is no connection between the worm wheel 52 and the cam 82. When moved outward, the keys cooperate with notches 87 in a flange on the worm wheel to complete a driving connection from the worm wheel. An odd number of notches are provided so that when one of the keys 83 fits into one of the notches 87 the other key is held in its inner position by one of the teeth 88 between the notches. With the parts in the position shown in Fig. 3 the upper key 83 is held in its inner position by a stop 89 which is integral with the plate 79. The lower key 83 is held in its inner position by engagement with a trip lever 90 which is connected on the upper end of the rock shaft 91 journaled in the ironer housing.

The linkage for operating the trip lever is shown in Fig. 9. It comprises a lever 92 pivoted at 93 on the underside of the table top and urged by a spring 94 against a stop 95. The lever 92 is provided with a knee pad 96 so that the lever can be actuated by a sidewise motion of the operator's knee. The lever 92 is connected by means of a link 97 to a crank 98 fixed to the lower end of the rock shaft 91. It is thus apparent that when the knee pad is moved to the right (Fig. 9) the shaft 91 will be pivoted in a counterclockwise direction thereby moving the trip lever 90 away from the lower key 83 and permitting the spring 84 to force it outward into one of the

notches 87, thus completing a driving connection from the worm wheel 52 to the cam 82. This key will now be termed the driving key. As soon as this driving connection is completed the lever 92 may be released and it will be returned to its normal position against the stop 95 by the spring 94. When the driving key is moved into one of the notches 87 the other key 83 is held in its inner position by one of the teeth 88. This is due to the fact there are an odd number of notches 87. The worm wheel 52 rotates in a clockwise direction, as viewed in Fig. 2, and the cam 82 is accordingly rotated in the same direction. When the cam 82 has rotated through 180 degrees the driving key is moved out of the notch 87 by engagement with the stop 89, thus breaking the driving connection to the cam. It is, therefore, apparent that upon each actuation of the lever 92 the cam 82 will be rotated through 180 degrees. The cam 82 engages a roller 99 journaled between the side walls of the projection 23. The cam operates with the roller 99 to pivot the arm 16 about the surface 25 so as to move the shoe toward and away from the roll. When the cam is in the position shown in Fig. 2 the shoe is away from the roll. When the cam is moved 180 degrees from this position the shoe is pressed against the roll. The projection 23 is of square cross-section and is slidably carried in a guide 100 in the plate 79, it being held in the guide by a plate 101 (Fig. 4). The projection 23 is provided with rectangular slots 102a through which the arm 16 rotatably extends. The rotation of the arm 16 in the slots 102a is limited by a pin 102 which is fixed in the arm and the ends of which extend through slots 103 in the side walls of the lever 23. One end of the pin 102 projects below the lever 23. Between this end of the pin 102 and the housing is connected a tension spring 104 which tends to turn the arm 16 in a clockwise direction, as viewed in Fig. 2. The clockwise movement of the arm 16 is permitted by the clearance between the pin 102 and the slots 103. The purpose of the spring 104 is to turn the arm 16 so that the upper or leading edge of the shoe will be spaced a greater distance from the roll when the shoe is moved away from the roll. This decreases the danger of burning the operator's hands while arranging material on the roll and also makes it easier to advance material of heavy thickness under the shoe. The spring 104 also serves to hold the roller 99 against the cam 82. When the cam is in the position shown in Fig. 2 the shoe is therefore moved away from the roll by the spring 104. When the shoe is pressed against the roll, the arm 16 turns in the slots 102a until the shoe is aligned with the roll. In this position the pin 102 is intermediate the ends of the slots 103. In the use of the ironer the material to be ironed is arranged on the roll, the shoe being away from the roll as shown in Fig. 6. The knee pad 96 is then moved to the right as viewed in Fig. 9 moving the trip lever 90 away from the adjacent key 83. The spring 84 moves the key 83 outward into one of the notches 87 in the continuously rotated worm wheel 52, thus completing a driving connection from the worm wheel to the cam 82. This key now becomes the driving key. The pressure on the knee pad 96 may now be released and the trip lever 90 will be returned to its normal position by the spring 94. After the completion of this driving connection the cam 82 rotates through 180 degrees at 75 which time the driving key is pushed inward

clear of the notches 81 by engagement with the stop 89. This breaks the driving connection between the worm wheel 52 and the cam 82. At this time the cam has rotated 180 degrees from the position shown in Fig. 2 and the shoe has been pressed against the roll by the projection 23. When the pressure between the shoe and the roll becomes greater than the force exerted by the springs 44 the roll is moved downward with respect to the tube 39, thus moving the internal gear 48 into engagement with the pinion 49 and completing a driving connection to the roll. Since the springs 44 are relatively weak compared to the pressure exerted by the shoe on the roll the driving connection to the roll is completed before the full ironing pressure is developed between the roll and the shoe. When the ironing operation is completed the knee pad 96 is again moved to the right causing the cam 82 to be rotated through 180 degrees in the manner described above. At the end of this movement the shoe is moved away from the roll by the spring 104 and the parts occupy the position shown in Fig. 2.

If the ironer is to be used for pressing, before actuating the knee pad 96 to cause the shoe to be pressed against the roll, the lever 62 is turned in a counterclockwise direction from the position shown in Fig. 1, thereby moving the flange 67 on the slide 56 between the tube 39 and the sleeve 38a. This prevents movement of the internal gear 48 toward pinion 49, thus preventing the establishment of the driving connection to the roll when the shoe is pressed against the roll.

What I claim as new and desire to secure by Letters Patent of the United States, is:

1. In an ironing machine, a pair of ironing members one of which comprises a roll and the other of which is movable into and out of pressing engagement with the roll, a frame carrying said members, a support, bearing means for the roll carried by said support, there being clearance between said support and said bearing means whereby said bearing means may move transversely relative to said support, a driving connection for said roll comprising gears one of which is carried by the frame and the other of which is carried by roll and is movable into and out of engagement with said first gear by transverse movement of the roll, spring means between said support and said bearing means for biasing said bearing means to a position in which said gears are separated, said spring means being relatively weak whereby it is overcome by the pressure exerted on the roll by the other pressing member, thereby permitting movement of the roll to a position in which said gears are engaged, power means for driving the gear carried by the frame and for shifting said movable ironing member into and out of engagement with the roll, a member movable between said support and said bearing means for holding said roll in a position in which said gears are separated, and a lever carried on said frame for moving said member between said bearing means and said support.

2. In an ironer, a roll, a shoe, a frame having means supporting the roll, an arm pivoted at an intermediate point on the frame and having a free end extending along the roll and movable toward and away from the roll, means on said free end supporting the shoe, means connected to the other end of the arm for pivoting the arm whereby the shoe is shifted toward and away from the roll, and means for displacing the

pivot for said arm relative to the frame whereby the shoe may be moved away from the roll independent of said shifting means.

3. In an ironer, a roll, a shoe, a frame having means for supporting the roll, an arm pivoted at an intermediate point on the frame and having a free end extending along the roll, means on said free end supporting the shoe, means connected to the other end of the arm for pivoting the arm whereby the shoe is shifted toward and away from the roll, the pivoting means for the arm including a lever pivoted on said frame and having a cam surface engaging said arm, said cam surface being shaped so that upon pivotal movement of the lever, the portion of the cam surface engaging the arm moves relative to the frame away from said roll, thereby permitting movement of the shoe away from the roll independent of said shifting means.
4. In an ironer, a roll, a shoe, a frame having means supporting the roll, an arm pivoted at an intermediate point on the frame and having a free end extending along the roll, means on said free end supporting the shoe, means connected to the other end of the arm for pivoting the arm about an axis perpendicular to the arm whereby the shoe is moved toward and away from the roll, and spring means for turning the arm about its axis whereby one edge of the shoe will be spaced from the roll a greater distance than at its other edge when the shoe is spaced from the roll.
5. In an ironer, a roll, a shoe, a frame having means supporting the roll, an arm pivoted on the frame and having a free end extending along the roll, means on said free end supporting the shoe, means for pivoting the arm about an axis perpendicular to the arm whereby the shoe is moved toward and away from the roll, and spring means for turning the arm about its axis whereby one edge of the shoe will be spaced from the roll a greater distance than at its other edge when the shoe is spaced from the roll.
6. In an ironer, a roll, an arm movable toward and away from the roll, a shoe, means for tiltably supporting the shoe at its center on said arm whereby the pressure between the roll and the shoe is equalized, stop means limiting the tilting movement of the shoe in one direction, and a leaf spring connected at one end to said arm and at the other end to said shoe for holding the shoe against said stop, one of said connections being releasable upon bending of the spring whereby the shoe may be removed from said arm.
7. In an ironer, a roll, an arm movable toward and away from the roll, a shoe, means for tiltably supporting the shoe at its center on said arm whereby the pressure between the roll and the shoe is equalized, stop means limiting the tilting movement of the shoe in one direction, and a leaf spring connected at one end to said arm and at the other end to said shoe for holding the shoe against said stop, one of said connections being a pin and slot connection releasable by bending of said spring whereby the shoe may be removed from said arm.

8. In an ironing machine, a pair of ironing members one of which comprises a roll, a driving connection for the roll comprising a driving gear and a driven gear, the driven gear being carried by the roll and being movable into and out of engagement with the other gear by movement of the roll transverse to its axis, shifting means for effecting engagement and separation of the ironing members and for moving the roll transverse

to its axis toward and away from the driving gear, and means supporting the roll for yielding bodily movement transverse to its axis independent of the position of said shifting means and away from said driving gear whereby the driven gear may, under the tooth reaction forces present when the teeth are misaligned, pause in its movement toward the driving gear to prevent clashing of the gear teeth.

9. In an ironing machine, a pair of ironing members one of which comprises a roll, one of said members being movable into and out of pressing engagement with the other, a driving connection for the roll comprising a driving gear and a driven gear, the driven gear being carried by the roll and being movable into and out of engagement with the driving gear by movement of the roll transverse to its axis, means for shifting said movable ironing member into and out of pressing engagement with the other ironing member and for moving the roll transverse to its axis toward and away from said driving gear, and means for supporting said ironing members, the support for the roll permitting yielding movement of the roll under the tooth reaction forces present when the teeth are misaligned transverse to its axis and independent of the

position of the shifting means and away from the driving gear upon operation of said shifting means to move the roll toward the driving gear.

- 5 10. In an ironing machine, a pair of ironing members one of which comprises a roll, one of said members being movable into and out of engagement with the other, a driving connection for the roll comprising an internal gear carried by the roll and a driving pinion within the internal gear, said internal gear being movable into and out of engagement with the pinion by movement of the roll transverse to its axis, means for shifting said movable ironing member into and out of engagement with the other ironing member and for moving the roll transverse to its axis toward and away from said pinion, and means for supporting the roll for yielding bodily movement transverse to its axis independent of the position of the shifting means and away from the pinion in response to actuation of the shifting means to move the roll toward the pinion whereby the internal gear may, under the tooth reaction forces present when the teeth are misaligned, pause in its movement toward the pinion to prevent clashing of the gear teeth.
